UNITED STATES PATENT OFFICE.

GROVER CLEVELAND SCOTT, OF WATSON, WEST VIRGINIA.

GLASS FINISHING AND POLISHING MACHINE.

Application filed June 20, 1921. Serial No. 478,854.

To all whom it may concern:

Be it known that I, GROVER CLEVELAND SCOTT, a citizen of the United States, and a resident of Watson, in the county of Marion and State of West Virginia, have invented certain new and useful Improvements in Glass Finishing and Polishing Machines, of which the following is a specification.

10 My present invention relates generally to drinking glass or tumbler machines and more particularly to a machine for smoothing the edges of pressed glassware in the nature of drinking glasses or tumblers as 15 well as polishing the external surface thereof, my object being the provision of a continuously operating machine capable of movement under either manual or mechanical power and of ready adjustment to accommodate glasses and tumblers of various 20 heights.

With these general objects in mind my invention resides in a machine constructed and operating as now described with respect to the accompanying drawings, which form a part of this specification and wherein,

Figure 1 is a side elevation of the complete machine,

Figure 2 is a top plan view thereof,

Figure 3 is a top plan view with the top plate removed,

Figure 4 is a horizontal section,

Figure 5 is a detail perspective view of the elevating mechanism,

Figure 6 is a detail perspective view of the cam controlling the elevating mechanism,

Figure 7 is a detail perspective view of the 40 polishing member,

Figure 8 is a detail perspective view of one of the glass holders,

Figure 9 is a detail perspective view of the shifting wheel, and

Figures 10 and 11 are partial perspective views showing a drinking glass or tumbler respectively before and after finishing.

It is a well known fact that pressed glasses are when initially formed slightly rough on the edges and of uncertain transparency, the first defect of which may be corrected by rotation of the glass in the presence of a flame playing on its edge until the latter is heated to a point closely approaching the molten state so that the material slightly runs and the roughness is

eradicated. The second defect may be overcome by polishing the external surface of the glass.

My improved machine provides for the 60 automatic accomplishment of both the smoothing of the edge of the glass and the external polishing thereof, and is utilized in connection with a heater such for instance as seen at 15 in Figures 1 and 2, having lower openings 16 upwardly into which the upper edges of glasses or tumblers may be projected into the influence of the flame from burners 17 or similar sources of heat. In accordance with my improvements glasses 70 are inserted first in one and then in the other of the openings 16 and successively subjected to the flame of the burners 17 while in rapid rotation, the operation being so timed that upon withdrawal of each glass 75 from the second opening the smoothing of its edge will have been accomplished.

In my improved machine a series of cup shaped upwardly opening glass holders 18 are mounted upon the upper ends of stems 80 19, the latter of which are journaled for rotation and vertical shifting movement in frames 20 secured to the outstanding portions 21 of spaced links of a chain 22. This chain travels horizontally upon the upper 85 surface of a table 23 and moves at opposite ends of the table around sprocket wheels 24 and 25 respectively secured upon the upper ends of upright shafts 26 and 27.

The shafts 26 and 27 rise from the lower 90 plates 28 of a pair of brackets 29 the upper ends of whose upright portions are secured by means of angle plates 30 to the central portion of the table 23 so as to support the latter. The lower end of shaft 27 is adjustably mounted in the plate 28 and its upper end is similarly adjustable in the slotted portion 31 of a supporting bar 32 within the opposite end of which the upper end of shaft 26 is journaled, this supporting bar 100 32 overlying the table 23 along the longitudinal axis of the latter and also overlying a cover plate 33 of the table, below the edge of which the outstanding links of the chain 22 project. This adjustment of shaft 27 provides for tightening or loosening of the chain 22 as may be desired.

Each of the stems 19 of the glass holders 18, one of which is shown in detail in Figure 8, has a spur gear 34 splined thereon, said spur gear being confined within the lower portion of the respective frame 20 for

engagement with the peripheral teeth of a large gear 35 journaled on the shaft 27 below the table 23, into connection with which each of the glass holders moves as it approaches one end of the table 23 in the clockwise rotation of the chain 22, beneath the elevated heater 15.

Gear 35 also has a downwardly presented toothed surface 36 and is provided at one point with a depending cam 37, teeth 36 being engaged by a pinion 38 in turn engaged by a gear 39 upon one end of a lower horizontal shaft 40. The opposite end of this shaft has a gear 41 engaging one side of the lower toothed edge of a horizontal gear wheel 42 the opposite side of the lower edge of which is connected by gears 43^a and 44^a of counter shafts 43 and 44 to the gear 45 of the shaft 46 of a motor 46. Thus during rotation of the motor 46 the gear 35 rotating the glass holders at one end of the machine is constantly rotated.

Shaft 26 at the opposite end of the table has a wheel 47 secured thereon and provided with a series of circumferentially spaced upwardly extending pins 48 each of the latter of which is adapted for engagement by the upstanding angular arm 49 secured on the horizontal gear wheel 42 previously described so that the wheel 47 will be partially rotated during each complete revolution of the gear wheel 42 and in this way bring about intermittent rotation of the chain 22. Each shifting movement of the chain 22 in a clockwise direction shifts a pair of the glass holders 18 to one end of the table upon relatively opposite sides of the longitudinal axis thereof and beneath the heater openings 16 at the same time brings these holders above an arcuate elevating plate 50 which is vertically shiftable below and adjacent to one end of the table 23 upon the upper end of a vertically shiftable stem 51. This elevating plate is of sufficient length to simultaneously engage the lower ends of the stems 19 of two of the cup holders in the operating positions previously described beneath the heater openings so that immediately following cessation of shifting movement of the chain 22, the plate 50 by its upward movement will engage and shift the glass holder stems 19 vertically to project the upper portions of the glasses 52 upwardly into the heater 15 through its openings 16. The elevating plate 50 may have, at one end, an adjustable stem engaging screw member 50^a as seen in Figure 5 so that each glass may if desired be lifted higher in the second opening of the furnace than in the first opening. By virtue of the splined connection of their gears 34 however and the fact that these gears are confined in the lower portion of the holder frames 20, said gears will remain in engagement with the gear 35 while at the operating station, both in

the upper and lower positions of the holders so that the latter particularly when inserted upwardly into the heater 15, will be constantly rotated.

It is obvious from the foregoing that in operation each glass holder will be shifted vertically at successive stages into the two heater openings during intermittent rotation of the chain 22 and it is further to be observed that as each glass holder is shifted toward and from beneath the heater its gear 34 will engage one of the idle gears 53 at opposite sides of the table in mesh with the horizontal gear 35 so that between shifting movements of the chain each glass holder while within the influence of the heater will be rotated to avoid ununiform heating. At the second rotating or polishing station the external surface of each glass will be rotated in contact with one concave face 54 of a polishing head 55, preferably formed of a suitable wood and mounted upon the upper end of a stem 56. This stem is journaled on the cover plate 33 and has diametrically outstanding arms 57 and 58 the latter of which is engaged by a spring 59 as shown particularly in Figure 2 in order to oscillate the polishing head to a position with its concave side turned toward the operating end of the machine for the ready reception of the mixed holder carried glass against its concave face. The stem 56 yields by rotation as the respective glass 52 continues its movement to the polishing station and, in the next intermittent shifting movement of the chain, passes from said polishing station and out of contact with the polishing head.

The elevating plate 50 has a lower inverted U-shaped piece 60 to which is pivotally connected the forward end of a lever 61 fulcrumed as at 62 upon the upper end of an upright 63 and engaged at its rear end by a spring 64 whose function is to shift the plate 50 upwardly, cam 37 engaging lever 61 to shift the plate 50 downwardly against the tension of spring 64, the latter of which operates under control of an adjustable screw stop 65 with which the spring engaged end of lever 61 contacts so as to limit upward movement of the elevating plate.

Thus each intermittent shifting movement of the chain 22 takes place while the cam 37 is in engagement with lever 61 and the elevating plate 50 is in lowermost position, and between these intermittent shifting movements the holders at the operating end of the machine are elevated by the spring 64.

The several parts above described in connection with the construction and operation of the machine are mounted upon a vertically adjustable platform 66 and this platform is in turn adjustable with respect to a base 67 by virtue of adjustable connect-

ing screws 68 therebetween, so that the entire working parts may be raised and lowered depending upon the particular ware in connection with which it is to be used, it

5 being understood that the glass or tumbler supporting cups 18 with their stems 19 may be removed and others inserted conforming to the size and shape of the articles to be finished.

10 The machine is thus adapted to glasses and tumblers of various sizes from small to large as well as those with and without stems, the finished articles being removed and unfinished ones substituted after they

15 have passed the polishing or burnishing station opposite the gear 53.

It is to be particularly noted that the articles are rotated not only when they are elevated within the heater 15 but also while 20 engaged with the burnishing or polishing head 54, at other times remaining stationary except for their intermittent shifting movement with and around the chain 22.

I claim:

25 1. A machine of the character described including an intermittently moving carrier in the form of a link chain, certain of the links of which have outstanding extensions, upright shafts at opposite ends of the car-

30 rier, a sprocket wheel on the upper end of each shaft, one of which is loose and the other of which is rigid with its respective shaft, means having connection with the last mentioned shaft for intermittently moving

35 the carrier chain, a gear revolvably mounted on the other shaft, means for constantly rotating the said gear, a frame secured to each of the said link extensions, a glass holder for each of the said frames including a stem

40 journaled vertically through the frame to slide vertically and rotate, a gear splined on each stem and confined against sliding movement therewith in the frame, said gears of said holders being engageable with the

45 first mentioned gear at one end of the carrier, and means at the said end of the carrier for shifting the stems of the holders vertically while in rotation.

2. A machine of the character described 50 including a table, a carrier movable around and upon the table, upright shafts, one of which is rotatable, carrier actuating mem-

55 bers on the shafts, a gear wheel loose on the other shaft, means for intermittently rotat-

60 ing the first shaft and thus moving the car-

65 rier, means for constantly rotating said gear, a vertically shiftable member adjacent to the gear, a cam rotating with the gear for actuating said shiftable member, a plurality

66 of glass holders each having a stem mov-

and shift vertically, and in which the gear of said stem is freely rotatable and confined against vertical shifting movement with the stem.

3. A machine of the character described 70 including a table, a carrier movable around and upon the table, upright shafts, one of

which is rotatable, carrier actuating mem-

bers on the shafts, a gear wheel loose on the other shaft, means for intermittently rotat-

75 ing the first shaft and thus moving the car-

rier, means for constantly rotating said gear,

a vertically shiftable member adjacent to the gear, a cam rotating with the gear for

actuating said shiftable member, a plurality

80 of glass holders each having a stem movable with the carrier above said shiftable mem-

ber, and a gear splined on the stem and en-

gageable with the first named gear, and a

frame on the carrier for each holder, in

85 which the holder stem is journaled to rotate and shift vertically, and in which the gear of said stem is freely rotatable and confined

against vertical shifting movement with the

stem, and a vertically adjustable support for

90 said mechanism consisting of a platform on

which the mechanism is mounted, and a base

with which the platform is adjustably as-

95 sociated.

4. A machine of the character described

including an intermittently movable car-

rier of endless form, a plurality of glass

holders supported at spaced points there-

around and movable therewith, each of said

holders being independently rotatable and

vertically shiftable, a constantly rotating

gear adjacent to one end of the carrier and

into and out of engagement with which the

holders are successively shiftable during

their movement with the carrier and means

105 engageable with the holders while the latter

are in engagement with the rotating gear,

for shifting the holders vertically with re-

spect to the carrier.

5. A machine of the character described

110 including an intermittently movable car-

rier of endless form, a plurality of glass

holders supported at spaced points there-

around and movable therewith, each of said

holders being independently rotatable and

vertically shiftable, a constantly rotating

gear adjacent to one end of the carrier and

with which the holders are successively en-

gageable during their movement with the

carrier, and means engageable with the

holders while the latter are in engagement

120 with the rotating gear, for shifting the

holders vertically with respect to the car-

rier, said means including an arcuate elevat-

125 ing plate, a lever one end of which is piv-

otally connected to the said plate, a con-

trolling spring engaging the opposite end

of the lever, to hold the elevating plate in

its upper position, and a cam rotating in

connection with the said gear and engage-

130

able with the lever to depress the elevating plate.

6. A machine of the character described including an intermittently movable carrier of endless form, a plurality of glass holders supported at spaced points there-around and movable therewith, each of said holders being independently rotatable and vertically shiftable, a constantly rotating gear adjacent to one end of the carrier and with which the holders are successively engageable during their movement with the carrier, and means engageable with the holders while the latter are in engagement with the rotating gear, for shifting the holders vertically with respect to the carrier, said means including an arcuate elevating plate, a lever one end of which is pivotally connected to the said plate, a controlling spring engaging the opposite end of the lever, to hold the elevating plate in its upper position, a cam rotating in connection with the said gear and engageable with the lever to depress the elevating plate, and means engaging the spring controlled end of the lever to regulate the extent of upward movement of the elevating plate under the tension of the spring.

7. A machine of the character described including an intermittently movable carrier of endless form, a plurality of glass holders supported at spaced points there-around and movable therewith, each of said holders being independently rotatable and vertically shiftable, a constantly rotating gear adjacent to one end of the carrier and with which the holders are successively engageable during their movement with the carrier, and means engageable with the holders while the latter are in engagement with the rotating gear, for shifting the holders vertically with respect to the carrier, said means including an arcuate elevating plate, a lever one end of which is pivotally connected to the said plate, a controlling spring engaging the opposite end of the lever, to hold the elevating plate in its upper position, a cam rotating in connection with the said gear and engageable with the

lever to depress the elevating plate, a bracket, and an adjusting screw threaded in the bracket and forming an adjustable stop for the spring controlled end of the lever for the purpose described.

8. A machine of the character described comprising a table, an endless flexible carrier on the table including a plurality of rotatable and vertically shiftable glass holders, sprockets between and around which said carrier travels, connections for independently rotating the said holders during a portion of their movement with the carrier including a gear on the shaft of one of said sprockets, means to intermittently move the carrier, and means to shift the holders vertically while rotating and between periods of movement of the carrier as described.

9. A machine of the character described including an intermittently moving carrier, a plurality of independently rotatable glass holders supported by and movable with the carrier, a table on which the carrier operates, means for moving the carrier, means with which the holders are shiftable into and out of engagement for rotating the holders, and a polishing head mounted to oscillate on the table and disposed in the path of movement of the holders to engage the latter while they are in rotation.

10. A machine of the character described including an intermittently moving carrier, a plurality of independently rotatable glass holders supported by and movable with the carrier, a table on which the carrier operates, means for moving the carrier, means with which the holders are shiftable into and out of engagement for rotating the holders, and a polishing head mounted to oscillate on the table and disposed in the path of movement of the holders to engage the latter while they are in rotation, said polishing head having a concave glass engaging surface and having outstanding arms, and a spring controlling oscillation of the head engaging one of said arms.

GROVER CLEVELAND SCOTT.
